DEVICE FOR HEATING THE INTERNAL MERCURY VAPOR HIGH VACUUM PUMPS OF RECTIFIERS

Application filed July 21, 1924, Serial No. 727,398, and in Germany July 30, 1923.

It is known in rectifiers to build the mercury vapor high-vacuum pump into the rectifier vessel itself. It is also known, in the case of mercury vapor pumps that are not built-in, to pass the exciting current of the rectifier in the form of a heating current through the heating winding of the pump. According to the invention, the heating winding in built-in pumps can be dispensed with by using at least one exciting anode as the heating body for the pump. The heat liberated in the voltage drop of the anode serves to evaporate the mercury of the pump.

The drawing illustrates diagrammatically a constructional example of the invention. The cooling dome *b* of the rectifier *a*, at the uppermost part of which is provided the connection *i* for the preliminary vacuum pump, serves at the same time as a condensing chamber for the mercury of the high-vacuum pump, which is situated in the vessel *c*. This latter is heated by means of the exciting anode *d*, which is constructed in the form of a plate.

In order to enable more energy to be liberated at this heating anode than at the other exciting anodes (not shown), the secondary side of the exciting transformer *e* is made asymmetrical. Moreover, the phase voltage in the heating anode phase is greater than in the other exciting phases. In addition to this, resistances and reactances *f*, *g* are disposed as shown between the exciting transformer *e* and the anodes, these resistances being chosen smaller in the heating anode phase *f* than in the other exciting phases *g*. The neutral point of the exciting transformer *e* is directly connected to the cathode *k* of the rectifier, but could also be connected therewith through a choking coil.

Several exciting anodes could also be used to heat the high vacuum pump. The ignition anode *h*, which can also be connected to the

exciting transformer, cannot of course be used to heat the pump *c*.

What I claim is:—

1. In a mercury vapor discharge device, an enclosing vessel, a plurality of electrodes for maintaining a mercury vapor discharge in said vessel, one of said electrodes being a mercury cathode said vessel having an exhaust opening, and a mercury vapor condensation pump consisting in part of a portion of said vessel and being in communication therewith for expelling gases through said opening, the energy for operating said mercury vapor pump being part of the energy dissipated in the discharge in said vessel. 60

2. In an electric vapor rectifier, an enclosing casing, a mercury cathode within said casing, anode means operating with said cathode to maintain a discharge within said casing, said casing having an exhaust opening for evacuating the same, and means for utilizing the energy dissipated at said anode means for generating a vapor blast evacuating said casing through said opening. 65

3. In an electric current rectifier of the arc type, a casing having an exhaust port, anodes within said casing, a mercury cathode within said casing and cooperating with said anodes to maintain an arc therebetween, and vapor discharging means disposed within and cooperating with said casing to evacuate the same, the energy dissipated at one of said anodes being used for generating the vapor discharged from said means. 70

4. In an electric current rectifier of the arc type, a casing having an exhaust port, an anode of plate-shape within said casing, a mercury cathode within said casing and cooperating with said anode to maintain an arc therebetween, and vapor discharging means disposed within and cooperating with said casing to evacuate the same, the energy dissipated at said plate-shaped anode being used for generating the vapor discharged from said means. 85 90

5. In an electric current rectifier of the arc type, a casing having an exhaust port, a mercury cathode in said casing, a plurality of exciting anodes for maintaining the mercury of said cathode in ionized condition, vapor discharging means disposed within and cooperating with said casing for evacuating the same, the energy dissipated at one of said exciting anodes being supplied to said means for producing a vapor blast therefrom, and means for so distributing the energy supplied to such exciting anodes as to dissipate a greater amount of energy at said anode providing the energy for said vapor discharging means than at the others of said anodes.

In testimony whereof I have signed my name to this specification.

WALTER DÄLLENBACH.
